CHARLES M. SIMPSON, OF HOUSTON, TEXAS, ASSIGNOR OF FIVE-SIXTHS TO HOWARD F. SMITH, OF HOUSTON, TEXAS.

BRIDLE-ROD.

1,127,927.

Specification of Letters Patent.

Patented Feb. 9, 1915.

Application filed April 17, 1914. Serial No. 832,536.

To all whom it may concern:

Be it known that I, CHARLES M. SIMPSON, a citizen of the United States, residing at Houston, in the county of Harris and State of Texas, have invented certain new and useful Improvements in Bridle-Rods, of which the following is a specification.

This invention relates to new and useful improvements in bridle rods.

10. The object of the invention is to provide a device of the character described designed to be used in railway track construction for the purpose of securing the rails of a temporary or unfinished track in a fixed position relative to each other while the train is passing thereover.

Another feature of the invention consists in the provision of means whereby the device may be adjusted to accommodate itself 20 to rails of different sizes.

With the above and other objects in view, the invention has particular relation to certain novel features of construction, operation and arrangement of parts, an example 25 of which is given in this specification and illustrated in the accompanying drawings, wherein—

Figure 1 is a side elevation of the device secured in position on the rails. Fig. 2 is a 30 side elevation thereof, showing the parts in position to be attached to the rails. Fig. 3 is a plan view of the device with the parts in the same position as that of Fig. 2, and Fig. 4 is a sectional end view of the device, 35 taken on the line *a—a* of Fig. 2.

Referring now more particularly to the drawings, the numerals 1 and 2 refer, respectively, to the railway rails, to be fixed in position by the bridle rod.

40. In track repairing and construction it is often necessary for trains to pass over the track while the same is being repaired and at times when the rails are not secured to the ties and at such times it is necessary to provide a means for temporarily holding the rails in position while the train is passing thereover and it is desirable that the means employed be so constructed as to be quickly and easily placed in position and removed.

45. For the above mentioned purpose the device has been provided, which will now be specifically described.

The numeral 3 refers to a sleeve, formed of suitable metal which may be of any desired shape but is preferably oblong in cross

section and is provided to receive the inner ends of the respective metallic straps 4 and 5, which said inner ends are inserted in the respective ends of the sleeve 3 and are readily slideable therein. The outer ends of the 50 respective straps 4 and 5 have the upturned hooks 6 and 7, provided to engage over the outer flanges of the respective rails 1 and 2, as shown in Fig. 1, when the device is engaged upon the rails. In the preferred 55 form of the device the straps 4 and 5 are flat and each at its mid portion is twisted, or given a quarter turn, so that the inner end will extend vertically edge wise and the outer end will extend horizontally edgewise 60 and fit up close against the under side of its respective rail.

The strap 4 is secured in the sleeve 3 by means of the bolt 8 which passes transversely through said sleeve and strap and the 65 inner end of said strap has a plurality of orifices 9 aligned therewith provided for the purpose of the lengthwise adjustment of the strap 4 in the sleeve 3. This adjustment is necessary because rail flanges differ in 70 width, some being wider than others. The straps 4 and 5 have the respective braces 10 and 11 pivoted thereto near their outer ends, but on the inner side of the respective rails 1 and 2. The outer ends of these braces are 75 slightly upturned and shouldered so as to fit closely over the inner edges of the rail flanges, when brought into alignment with their respective straps 4 and 5, as shown in Fig. 1. The braces 10 and 11, respectively, 80 are pivoted to their respective straps by means of the respective bolts 12 and 13 which extend through aligned vertically extending orifices. The said straps are provided with a plurality of orifices 14 and 15 85 arranged at different distances from the respective rails 1 and 2 to provide for the adjustment of said braces. This adjustment is necessary on account of the different widths of rail flanges, as hereinbefore explained. The respective straps 4 and 5 have the respective rings 16 and 17 slidably mounted thereon and provided to be slipped over the inner ends of the respective braces 10 and 11 so as to hold them in position 90 when engaged over the rail flanges. A U-shaped member 18 is provided, the open end of which embraces the sleeve 3 and is pivoted to the center thereof by means of the transverse bolt 19. This member, or yoke, 95

100

105

110

is provided to engage in the notch 20 in the upper edge of the strap 5, when the device is engaged on the rail, as shown in Fig. 1 and locks said strap against lengthwise movement relative to the sleeve 3. When the yoke 18 is in its engaging position, it is secured therein by means of the bolt 21 which passes through alined orifices extending transversely through said yoke, sleeve 10 and strap.

The application of the device is as follows:—When it is desired to secure the device on the rail, the bolt 21 is removed and the yoke 18 is disengaged from the notch 20. The rings 16 and 17 are also disengaged from the inner ends of the braces 10 and 11 and said braces turned around at right angles to their supporting strap, as shown in Figs. 2 and 3. The device is then placed under the rails and the hook 6 engaged over the outer flange of the rail 1. The strap 5 is then forced inwardly until the hook 7 engages over the outer flanges of the rail 2 and the yoke 18 engages in the notch 20. The braces 10 and 11 are then brought into alinement with their respective straps in which position their inner ends will engage over the inner flanges of the respective rails 1 and 2 and said braces are secured in position by slipping the rings 16 and 17 over their inner ends. The bolt 21 is then secured in position and the yoke thereby locked in engagement in the notch 20.

What I claim is:—

1. A device of the character described including a sleeve, two oblong members whose inner ends extend into said sleeve, a hook carried by the outer end of each of said members, said hooks being provided to engage over the outer flanges of the rails forming a railway track, a brace pivoted to each of said members, the outer ends of said braces engaging over the inner flanges of said rails when the braces are brought into alinement with their respective members,

means for locking said braces in engagement with said rail flanges, a yoke pivoted to the sleeve for engaging with one of said members and locking the same against lengthwise movement relative to the sleeve. 50

2. A device of the character described including a sleeve, two oblong members whose inner ends extend into said sleeve, a hook carried by the outer end of each of said members, said hooks being provided to engage over the outer flanges of the rails forming a railway track, a brace pivoted to each of said members, the outer ends of said braces engaging over the inner flanges of said rails when the braces are brought into 60 alinement with their respective members and a slidably mounted ring carried by each of said oblong members and provided to engage over said braces and secure them in position in engagement with said rail 65 flanges.

3. A device of the character described including a sleeve, two oblong members whose inner ends extend into said sleeve, a hook carried by the outer end of each of said 70 members, said hooks being provided to engage over the outer flanges of the rails forming a railway track, a brace pivoted to each of said members, the outer ends of said braces engaging over the inner flanges of 75 said rails, when the braces are brought into alinement with their respective members, means for locking said braces in engagement with said rail flanges, means pivoted to the sleeve and engaging with one of said members and locking the same against lengthwise movement relative to the sleeve. 80

In testimony whereof I have signed my name to this specification in the presence of two subscribing witnesses.

CHARLES M. SIMPSON.
